(57) **CLAIM**

The ornamental design for an automotive monitoring camera, as shown and described.

DESCRIPTION

FIG. 1 is a top, front and left perspective view of an automotive monitoring camera showing my new design; FIG. 2 is a bottom and front perspective view thereof; FIG. 3 is a front elevation view thereof; FIG. 4 is rear elevation view thereof; FIG. 5 is a right elevation view thereof; FIG. 6 is a left elevation view thereof; FIG. 7 is a top plan view thereof; FIG. 8 is a bottom plan view thereof; and, FIG. 9 is a top, front and left perspective view thereof, shown in a collapsed configuration.

The broken lines depict portions of the automotive monitoring camera in which the design is embodied that form no part of the claimed design.
